UNITED STATES PATENT OFFICE.

BENJAMIN V. GILMORE, OF GAULEY BRIDGE, WEST VIRGINIA.

INNER-TUBE BOOT.

Application filed September 22, 1926. Serial No. 137,059.

This invention relates to an improved inner tube boot and seeks, among other objects, to provide a device of this character which, even though the tire casing is badly 5 torn or severed, as by a blow out will, nevertheless, effectually retain and protect the inner tube at the rupture in the casing.

The invention seeks, as a further object, to provide a boot wherein, when applied, 10 the body of the boot will be retained against bulging by retaining straps wrapped in opposite directions about the body.

And the invention seeks, as a still further object, to provide a boot wherein, when 15 the boot is applied, said straps will be securely anchored.

In the drawings:

Figure 1 is a perspective view of my improved boot.

20 Figure 2 is a sectional view showing the boot applied and taken through the boot at one of the retaining straps thereof.

Figure 3 is a view similar to Figure 2, taken through the boot at the other of the 25 retaining straps thereof.

In carrying the invention into effect, I employ an arcuate boot body 10 transversely curved to fit an inner tube and, of course, the body will be made in different sizes to 30 suit the varying dimensions of different inner tubes. At its inner radius, the body is meditately split longitudinally from end to end to provide sides 11 having square edges 12 and while any suitable material may be 35 employed in forming the body still, said body is preferably constructed of rubber and fabric or cord laminations vulcanized into a composite unit. In any event, the body includes a preferably canvas back 13 40 which covers practically the whole of the outer side of the body, said back terminating flush with the edges 12 of the sides of the body and close to the ends thereof, and integral with said back is a pair of retaining straps 14 extending from opposite edges 45 of the back near the ends thereof. These straps are preferably oblong in configuration, being of corresponding uniform width, and, as will be observed, the inner longitudinal edges of the straps both touch the transverse center line of the body. The 50 ends of the body are respectively skived, as indicated at 15, to a feather edge, so as to form a smooth joint with a tire casing and sewed or otherwise secured to the inner free longitudinal margin of one of the sides

11 of the body is a relatively soft and pliable flap 16 which projects beyond the ends of the body and is skived at its ends respectively, as indicated at 17, to a feather edge 60 so as to form a smooth joint with an inner tube. The flap 16 is preferably of rubber.

In Figures 2 and 3 of the drawings, I have shown the flap applied, a conventional rim being indicated at 18, tire casing at 19 65 and inner tube at 20. Initially, the body 10 is placed about the inner tube 20 and the edges 12 of the sides 11 thereof brought into abutting relation when, as shown, the flap 16 will overlie the joint between said edges 70 for protecting the inner tube. The straps 14 are then wrapped, in opposite directions, snugly about the body and, as will be observed, said straps are each of a length to extend once about the body with a remaining free end. The tire casing 19 with the inner tube therein, is then applied to the rim 18 when, as shown in Figure 2, the free end of one of the straps 14 is inserted beneath one of the beads of the tire casing to 75 extend between said bead and the adjacent side flange of the rim, and the other of the straps 14 inserted, as shown in Figure 3, beneath the other bead of the tire casing to 80 extend between such latter bead and the other side flange of the rim. As will be observed, the straps are of such length that the projecting terminals thereof may be 85 grasped for pulling the straps more or less taut about the boot body and, after the tire has been inflated, said projecting terminals may, if desired, be cut off flush with the free edges of the side flanges of the rim 90 so as to avoid an otherwise possible unsightly appearance of said terminals.

As will now be seen, when the tire is inflated, the ends of the straps 14 will be firmly anchored between the beads of the tire casing and the rim so that these straps will thus serve to reinforce and retain the boot body against the bulging pressure of the inner tube. Premature failure of the boot will thus be precluded and furthermore, the boot will serve to retain the inner tube even though the tire casing is badly torn or ruptured. Since, as will be understood in view of the foregoing, the combined width of the straps 14 is nearly equal to the length of the boot body and since each of the straps extends entirely around the body, 105 said straps will form a protecting covering for the body, reinforcing the body against 110

rupture while, at the same time, the straps will individually tend to snub the body against opening movement at the joint between the sides thereof.

5 Having thus described the invention, I claim:

1. An inner tube boot including a body having sides and provided with retaining straps extending from said sides and disposed to be wrapped in opposite directions about the body, said straps having a combined width to form a protecting covering for the body when wrapped thereabout.

2. An inner tube boot including a body having sides and provided with a back having straps extending from said sides and disposed to be wrapped in opposite directions about the body.

3. An inner tube boot including a split body provided with a back having straps extending from opposite edges thereof and disposed to be wrapped in opposite directions about the body over the split therein.

4. An inner tube boot including a split body having straps disposed to extend in

crossed relation beneath the beads of a tire casing to be anchored between said beads and a rim for retaining the body against opening movement at the split therein.

5. An inner tube boot including a split body having straps disposed to be wrapped in opposite directions about the body over the split therein to extend at their free ends in crossed relation beneath the beads of a tire casing to be anchored between said beads and a rim for retaining the body against opening movement at the split therein.

6. The combination with a rim, a casing therein having beads, and an inner tube within the casing, of a split boot embracing the inner tube and provided with straps extending in crossed relation beneath the beads of the tire casing and anchored between said beads and the rim for retaining the boot against opening movement at the split therein.

In testimony whereof I affix my signature.

BENJAMIN V. GILMORE. [L. s.].
